UNITED STATES PATENT OFFICE.

VICTOR EMILIUSS HANSEN, OF BROOKLYN, NEW YORK, ASSIGNOR TO INTERNATIONAL CIGAR MACHINERY COMPANY, OF NEW YORK, N. Y., A CORPORATION OF NEW JERSEY.

CIGAR-BUNCH MANIPULATOR.

1,188,540.

Specification of Letters Patent. Patented June 27, 1916.

Application filed April 8, 1915. Serial No. 20,006.

To all whom it may concern:

Be it known that I, VICTOR EMILIUSS HANSEN, a citizen of the United States, residing at Brooklyn, county of Kings, and State 5 of New York, have invented a new and useful Improvement in Cigar-Bunch Manipulators, of which the following is a specification.

This invention relates to an improvement 10 in cigar bunch manipulators, particularly adaptable for use in cigar making machines.

In making cigars by machinery, a charge 15 of filler tobacco is first measured and rolled within a binder, usually by means of a Chianti belt mechanism, to form a bunch. If the cigar is to be what is known in the art as a "fresh bunch cigar", the bunch formed in the Chianti belt mechanism has a wrapper applied thereto very soon after the 20 formation of the bunch and while the tobacco of which the bunch is composed is soft and pliable. The rolling of the filler charge within the binder during the formation of the bunch, however, almost invariably results in compacting the filler within the 25 binder unevenly. It is therefore customary, in cigar machines for making fresh bunch cigars, to introduce a cigar bunch manipulating mechanism which acts upon the bunch 30 after it is formed in the Chianti belt mechanism and before it goes to the wrapping mechanism where the wrapper is applied thereto.

Various types of bunch manipulators have 35 been heretofore used, all of which were more or less successful, but none of which have proved capable of manipulating the bunch in a perfect manner.

The principal object of the present invention is the production of a cigar bunch manipulator acting upon a bunch immediately after it is formed in the Chianti belt mechanism or equivalent mechanism, for insuring a more perfect manipulation of the 45 bunch to distribute the filler material evenly throughout the bunch within the binder.

Another object of the invention is the production of a device of this kind which is simple, inexpensive, entirely automatic in 50 action, and not liable to derangement or excessive wear. With these and other objects not specifically mentioned in view, the invention consists in certain constructions and combinations which will be hereinafter fully

described and then specifically set forth in 55 the claims hereunto appended.

In the accompanying drawings, which form a part of this specification and in which like characters of reference indicate the same or like parts, Figure 1 is a side elevation, 60 partly broken away, of a device constructed in accordance with the invention. Fig. 2 is an end elevation of the device illustrated in Fig. 1. Fig. 3 is a sectional elevation of a portion of the device illustrated in Figs. 65 1 and 2. And Fig. 4 is a fragmentary detail view of means for transporting a cigar bunch away from the cigar bunch manipulator.

In carrying the invention into effect, 70 there is provided a pair of bunch rolling members having oppositely disposed operating surfaces spaced apart a distance less than the diameter of a cigar bunch so that a bunch located between said surfaces will 75 be slightly squeezed diametrically to move the filler material within the bunch. There is also provided means for producing a relative movement of said members whereby the bunch is rolled between said surfaces to progressively alter the diametrical slight compression of the bunch as it rolls along in order to work the compacted portions of the 80 filler material into the space occupied by the relatively loose portions of filler material. 85 There is further provided a fluctuant mount for one of said members which is adapted to be brought into action by a bunch rolling between said surfaces, this mount being so arranged that a varying pressure is applied 90 to the bunch as it rolls between the surfaces to effect a final even distribution of the filler material within the binder. In the best constructions there is also provided means for automatically introducing a cigar bunch 95 between said members, and means for transporting a bunch away from said members. In some constructions there is also provided a support to which the transporting means 100 delivers bunches. And in some constructions also there is provided a Chianti belt mechanism adapted to initially form a bunch. All of the above mentioned elements may be varied in construction within wide limits.

The device selected to illustrate the invention is but one of many possible concrete embodiments of the same and the invention

is therefore not to be restricted to the precise details of the structure shown and described.

Referring to the drawings, 1 indicates a rolling table, and 2 indicates an apron or Chianti belt coöperating with the table. This Chianti belt is engaged by a roller 3 carried in adjustable bearings 4 mounted in levers 5, one on either side of the table 1. 10 This lever carries a bowl 6 tracking on a cam 7 located beneath the table 1, the purpose of this cam 7 and roller 6 being to give the roller 3 an upward movement at the end of the bunch forming operation, to permit 15 the bunch to pass under the roller 3 and to be delivered into a bunch rolling manipulator to be hereinafter described. Otherwise, this Chianti belt mechanism is the same as the ordinary Chianti belt mechanism well known in the art; and since the 20 particular construction of the Chianti belt mechanism lies wholly outside of the present invention, a more complete illustration and description of the same is omitted herefrom 25 in the interest of brevity and clearness.

Located adjacent the delivery end of the Chianti belt mechanism is a bunch manipulator; and while in some constructions it may be otherwise constructed; as shown, 30 this bunch manipulator includes a constantly rotating drum 8, the surface of which is knurled and provided with one or more depressed channels 9, the function of which will be hereinafter described. The 35 drum 8 is loosely mounted upon a shaft 10 journaled in bearings 11-12 formed in uprights 13-14 rising from a base 15. Secured to the drum 8 is a pinion 16, by means of which said drum is rotated in the direction of the arrow in Fig. 1. This pinion is 40 in engagement with a gear 17 which is fast upon a short shaft 18 journaled in a swinging arm 19, this arm being swingable about the axis of the shaft 10. The arm 19 projects beyond the shaft 18, and at its extreme 45 end is provided with an outward bend 20 which is clamped to the upright 14 by means of a clamping screw 21, this screw working in a slot 22 formed in the upright 14. The 50 shaft 18 also carries a sprocket 23 over which runs a chain 24, shown in full in Fig. 2 and indicated by a broken line in Fig. 1. This chain also runs over a sprocket 25, which sprocket is fast on the shaft 10. The 55 shaft 10 also carries a cam 26. The chain 24 derives its motion from any suitable source of motion and the gear 17 derives its motion from the chain. The cam 26 is rotated by the chain 24 in a direction opposite to the direction of the drum 8 and at a slower speed. The arm 19 is made adjustable so that it can be used to take up any slack there may be in the driving chain 24.

Coöperating with the operating surface 60 of the drum 8 and spaced apart from said

surface a distance less than the diameter of a bunch to be manipulated is a segmental coöperating rolling member made in two sections marked 27-28, these two sections being hinged together on a pintle 29. This 70 pintle is movable so that the distance between the operating surface of the drum 8 and the operating surface of the coöperating member 27-28 may be varied. To permit 75 of this movement, the pintle 29 is fixed in the ends of arms 30, which arms are tied together by means of a web 31 extending from one to the other. The arms 30 are fast upon a rock shaft 32 adjacent the web 31, and this rock shaft is pivoted on adjustable 80 pivots 33 threaded into the uprights 13 and 14 before referred to. Projecting from the web 31 is an arm 34 carrying an adjusting screw 35. This adjusting screw abuts against a web 36 rising from the base 15 85 before referred to. By means of the structure just described, the pintle 29 may be adjusted toward or away from the operating surface of the bunch rolling drum 8.

The section 27 of the segmental rolling 90 member has a spur 37 through which is threaded an adjusting screw 38 and through which is passed an adjusting bolt 39. The adjusting screw 38 contacts with a boss 40 formed on the section 28, while the bolt 39 95 is threaded into said boss. By means of this adjusting screw and bolt, the sections 27 and 28 may be relatively adjusted so that when the pintle 29 is moved away from the drum 8 to provide a larger space between 100 said drum and the coöperating rolling member, the sections of the member may be relatively adjusted to also provide a larger space between the drum and the extreme ends of said sections in order to maintain 105 the normal concentric relation of the drum and the coöperating segmental rolling member.

It is not desirable that the segmental coöperating member be held in unchanging 110 position with respect to the operating surface of the drum 8. On the contrary, it is desirable that it move during the operation of the device, and a fluctuant mount is provided for this purpose. While in some constructions another form of mount may be used; as shown, this fluctuant mount includes a floating yoke 41 provided with jaws 42 normally engaging the pintle 29 before referred to, and also carrying adjusting screws 43 contacting with bosses 44 and 45 formed respectively on the under side of the sections 27 and 29 before referred to. The yoke 41 is provided with a stem 46, the free end of which is guided in a pocket 47 120 formed in the base 15. The stem 46 is further provided with a pair of adjusting nuts 48, and between these adjusting nuts and the base 15 is a spring 49 which is coiled around the stem. The thrust of this 125

spring is upwardly and toward the drum 8 so that it normally holds the yoke 41 and the arms 30 in the position shown in Fig. 1, the upward thrust being resisted by the adjusting screw 35 and abutment 36 before described.

At the delivery end of the section 27 there is located a pair of thin plate springs 50 which are screwed to the section 27 and which project into the space between the extreme end of the section 27 and the drum 8. That portion of the springs 50 lying in the space between the section 27 and the drum 8 is provided with a reentrant bend marked 51. The purpose of this spring is to retain a bunch after it has passed between the drum 8 and the segmental coöperating rolling member 27-28.

After a bunch has been manipulated in the mechanism so far described and delivered to a position just beyond the spring 50, it may be removed from the bunch manipulator, and in the device selected to illustrate the invention mechanism is provided for this purpose. This mechanism includes a pair of swinging arms 52, these arms being tied together at one end by a web 53 and at the other or outer end by a web 54. The arms are fulcrumed upon a shaft 55 mounted in suitable bearings carried by the uprights 13 and 14 before referred to. The shaft 55 carries a pinion 56 which is in mesh with a sector gear 57. This sector gear is fast upon a short shaft 58 journaled in a boss carried in the uprights 13 and 14, and the shaft also carries a cam lever 59, which in turn carries a bowl 60 tracking in a cam groove 61 formed in the cam 26 before referred to. By means of this mechanism, the arms 52 are swung from receiving to delivery position. The outer ends of the arms 52 carry a pintle 62, and upon this pintle is clamped a bunch retaining jaw 63. Fixed upon the web 54 are a pair of fingers 64 which are adapted to enter the grooves 9 in the surface of the drum 8 when the transporting device is in the bunch receiving position. The pintle 62 is provided with a short arm 65 which carries a stud 66. This stud engages a suitable slot 67 in an arm 68 fulcrumed on the shaft 55 before referred to.

A retaining spring 69 connects one of the arms 52 and the arm 68, the function of this spring being to retain the arms 52 and 68 in position on either side of a center to which they may be thrown; or in other words, to retain the bunch retaining jaw 63 in closed position during one movement, and to retain it in open position during the opposite movement of said arm. On one end of the shaft 55 is fixed a lever 70 carrying two limiting screws 71, one of these screws contacting with a post 72 secured in the upright 13 at one end of the arm movement, and the other screw contacting with the

same post at the other end of the arm movement. A similar lever 73 is formed integrally on the hub of the arm 68 and is provided with limiting screws 74 adapted for contact with a post 75 secured in the upright 14 before referred to. The levers 70 and 73 are independently adjustable so that at one end of the movement of the arms 52 the lever 68 is stopped before the arms 52 and the bunch retaining jaw is thereby closed; while at the other end of the movement a reverse action takes place so that the bunch retaining jaw 63 is opened and drops the bunch upon a support indicated diagrammatically at 76.

Fig. 1 illustrates a bunch about to be introduced between the operating surface of the drum 8 and the segmental coöperating member 27-28. By an inspection of this figure, it will be readily understood that when the Chianti belt 2 is straightened out, as indicated by dotted lines in Fig. 1, the bunch will be thrown into contact with the operating surface of the drum 8 and will thereby be rolled downwardly between the drum and the section 28. This tends to force the upper end of the section 28 radially outward, thus rocking the segmental coöperating member as a whole, and slightly depressing the spring 49. As the bunch rolls down between the two surfaces, the leverage decreases and when it reaches a point directly over the pintle 29, the thrust of the spring is direct and the diametrical compression of the bunch is then greater than at the time when the bunch is introduced between the coöperating surfaces. This increase in compression takes place gradually and progressively and reaches its maximum when the bunch is at the point directly over the pintle 29. From this point to the delivery end of the space between the rolling surfaces, the pressure gradually decreases and the segmental coöperating member rocks in the other direction. It will thus be seen that the pressure exerted upon the bunch is a fluctuating pressure gradually increasing and then gradually decreasing. This has been found to be highly advantageous in manipulating a bunch to secure an even distribution of the filler tobacco within the binder.

What is claimed is:

1. In a cigar bunch manipulator, the combination with a pair of bunch rolling members having oppositely disposed operating surfaces spaced apart a distance less than the diameter of a cigar bunch, of means for producing a relative movement of said members whereby a bunch is rolled between said surfaces, and a fluctuant mount for one of said members adapted to be brought into action by a bunch rolling between said surfaces.

2. In a cigar bunch manipulator, the com-

- 5 combination with a pair of bunch rolling members having oppositely disposed operating surfaces spaced apart a distance less than the diameter of a cigar bunch, of means for producing a relative movement of said members whereby a bunch is rolled between said surfaces, a fluctuant mount for one of said members adapted to be brought into action by a bunch rolling between said surfaces, 10 and means for introducing a cigar bunch between said members.
- 15 3. In a cigar bunch manipulator, the combination with a pair of bunch rolling members having oppositely disposed operating surfaces spaced apart a distance less than the diameter of a cigar bunch, of means for producing a relative movement of said members whereby a bunch is rolled between said surfaces, a fluctuant mount for one of said members adapted to be brought into action by a bunch rolling between said surfaces, means for introducing a cigar bunch between said members, and means for transporting a bunch away from said members.
- 20 25 4. In a cigar bunch manipulator, the combination with a pair of bunch rolling members having oppositely disposed operating surfaces spaced apart a distance less than the diameter of a cigar bunch, of means for producing a relative movement of said members whereby a bunch is rolled between said surfaces, a fluctuant mount for one of said members adapted to be brought into action by a bunch rolling between said surfaces, means for introducing a bunch between said members, means for transporting a bunch away from said members, and a support to which the transporting means delivers bunches.
- 30 35 40 5. In a cigar bunch manipulator, the combination with a pair of bunch rolling members having oppositely disposed operating surfaces spaced apart a distance less than the diameter of a cigar bunch, of means for producing a relative movement of said members whereby a bunch is rolled between said surfaces, a fluctuant mount for one of said members adapted to be brought into action by a bunch rolling between said surfaces, 45 and a Chianti belt mechanism adapted to initially form a bunch and then to introduce it between said members.
- 50 55 6. In a cigar bunch manipulator, the combination with a pair of bunch rolling members having oppositely disposed operating surfaces spaced apart a distance less than the diameter of a cigar bunch, of means for producing a relative movement of said members whereby a bunch is rolled between said surfaces, a fluctuant mount for one of said members adapted to be brought into action by a bunch rolling between said surfaces, a Chianti belt mechanism adapted to initially form a bunch and then to introduce it between said members, and a swinging carrier

for transporting a bunch from said members.

7. In a cigar bunch manipulator, the combination with a pair of rolling members having oppositely disposed operating surfaces spaced apart a distance less than the diameter of a bunch, of means for producing a relative movement of said members whereby a cigar bunch is rolled between said surfaces, a fluctuant mount for one of said members adapted to be brought into action by a bunch rolling between said surfaces, a Chianti belt mechanism adapted to initially form a bunch and then to introduce it between said members, a swinging carrier for transporting a bunch from said members, and a stationary support to which the swinging carrier delivers bunches.

8. In a cigar bunch manipulator, the combination with a constantly moving bunch rolling member, of a coöperating rolling member operative in fixed position and spaced from the moving member a distance less than the diameter of a bunch, and a fluctuant mount for the coöperating member adapted to be brought into action by a bunch rolling between said members.

9. In a cigar bunch manipulator, the combination with a constantly rotating bunch rolling drum, of a segmental coöperating bunch rolling member the operating surface of which is normally concentric with the operating surface of the drum and which is spaced from the surface of the drum a distance less than the diameter of a bunch, and a fluctuant mount for the coöperating member adapted to be brought into action by a bunch rolling between said members.

10. In a cigar bunch manipulator, the combination with a constantly rotating bunch rolling drum, of a segmental coöperating bunch rolling member the operating surface of which is normally concentric with the operating surface of the drum and which is spaced from the drum a distance less than the diameter of a bunch, said coöperating member being formed of two parts hinged together, and a fluctuant mount for the coöperating member adapted to be brought into action by a bunch rolling between said members.

11. In a cigar bunch manipulator, the combination with a constantly moving bunch rolling member, a coöperating bunch rolling member operative in fixed position and spaced from the moving member a distance less than the diameter of a bunch, and a fluctuant mount for the coöperating member adapted to be brought into action by a bunch rolling between said members, said mount comprising operative connections and a spring pressed yoke carrying means for normally adjusting the relative positions of the members.

12. In a cigar bunch manipulator, the

combination with a constantly moving bunch rolling member, of a coöperating bunch rolling member operative in fixed position and spaced from the moving member 5 a distance less than the diameter of a bunch, said coöperating member being formed of two parts hinged together, adjustable means for supporting said parts at the hinge, and a fluctuant mount for the coöperating member adapted to be brought into action by a bunch rolling between said members and comprising operating connections and a 10 spring pressed yoke normally engaging the parts at and adjacent the hinge and provided with means for normally adjusting the relative positions of said members.

13. In a cigar bunch manipulator, the combination with a constantly rotating bunch rolling drum, of a segmental coöperating bunch rolling member the operating surface of which is normally concentric with the operating surface of the drum and which is spaced from the drum a distance less than the diameter of a bunch, said segmental 20 member being formed of two parts hinged together, adjustable means for supporting said segmental coöperating member at the hinge, and a fluctuant mount for the coöperating member adapted to be brought into action by a bunch rolling between said members and comprising operating connections and a spring pressed yoke normally engaging the parts of the segmental member at and adjacent the hinge and provided with 25 means for normally adjusting the relative positions of the drum and coöperating segmental member.

14. In a cigar bunch manipulator, the combination with a constantly rotating 30 bunch rolling drum provided with a circumferential channel, of a segmental coöperating bunch rolling member the operating surface of which is normally concentric

with the operating surface of the drum and which is spaced from the surface of the drum a distance less than the diameter of a bunch, a fluctuant mount for the segmental coöperating member adapted to be brought into action by a bunch rolling between said members, and means for transporting a bunch away from the drum and coöperating member comprising operating connections and a bunch retaining finger adapted to move into the channel of the drum below the operating surface of said drum in order to engage the under side of a bunch as it is rolled forward between the drum and coöperating segmental member.

15. In a cigar bunch manipulator, the combination with a constantly rotating bunch rolling drum, of a segmental coöperating bunch rolling member the operating surface of which is normally concentric with the operating surface of the drum and which is spaced from the surface of the drum a distance less than the diameter of a bunch, a fluctuant mount for the segmental member adapted to be brought into action by a bunch rolling between said members, a spring detent carried by the segmental member and adapted to be moved out of the way by a bunch as it advances between the drum and segmental member and to snap in behind the bunch after the latter has passed said detent, and means for engaging the bunch just beyond the detent and for transporting it away from the drum and segmental member.

In testimony whereof, I have signed my name to this specification in the presence of two subscribing witnesses.
